ELECTRICAL DISCHARGE DEVICE

David Harker, Alplaus, N. Y., assignor to General
Electric Company, a corporation of New York

Application April 15, 1943, Serial No. 483,157

6 Claims. (Cl. 250—142)

The present invention relates to electrical discharge devices operating by virtue of the ionization of a highly attenuated gas and, in particular, provides an improved X-ray device.

It is one of the objects of my invention to provide an X-ray tube having a tubular extension of very small bore, e. g., one-fourth inch diameter. The extension is of such small diameter that it can be inserted for radiographic or therapeutic purposes into restricted orifices, such as the nasal passages of the human head. My invention, however, should not be considered as necessarily restricted to the medical field nor in fact to the X-ray field. The apparatus may be used, for example, for the production of cathode rays.

In the accompanying drawing Fig. 1 is a longitudinal section of an X-ray tube embodying my invention; Fig. 2 is a cross-section taken at 2—2 of Fig. 1 in the direction of the arrows; and Fig. 3 is a cross-section of a ray-emitting window in a modification.

The device shown is elongated and comprises the following communicating sections or housings or successively smaller diameter comprising a single sealed tubular envelope: (a) a cathode seal housing 3 (shown broken to conserve space), (b) a cathode housing 4 (also shown broken for the same reason), and (c) an anode housing 5. The housings 4 and 5 consist of metal tubes and are connected to ground. An anode or target 6 is located at the remote end of the tubular housing 5, the latter extending outwardly from the housing 4 and being aligned normal to the surface of a cathode 7, as shown in Fig. 1. When the device is intended to emit cathode rays, no separate target is required, as shown in Fig. 3, the beam of electrons or cathode rays then penetrate the end wall 2 which may be made thin. The cathode seal housing 3 contains an insulating zone, the remote end of this housing being at cathode potential.

The cathode 7, which is of the non-thermionic or "cold" cathode type, is supported on a tubular cathode stem 8 into which projects a conduit 9. The open end is joined by a vacuum-tight solder joint to disk 14. Conduit 9 supplies a cooling fluid as, for example, oil or water. The cooling medium leaves the conduit 9 (as indicated by the arrows), comes into contact with the closed end of the tube 8, and returns through the tube 8 from whence it is discharged by the conduit 10. Tubes 9 and 10 pass through a plate 25 to which they are joined by a watertight solder joint. The plate 25 is held in place by the threaded ring 24 and the washer 26. A cathode plate 11, which may consist of aluminum or beryllium, is held in close thermal contact with the tube 8 by a threaded ring 12. This particular form of cathode is shown for illus-

trative purposes. Other known forms of cathode may be used.

The end of the cathode housing 3 is closed by a disk 14 into which is sealed a thin metal cylinder 15 which is in turn sealed into a glass cylinder 16. A second thin metal cylinder 17 is sealed into the opposite (right-hand) end of the glass cylinder 16. This metal cylinder 17 is joined to a heavy ring 18. These cathode seal parts are mounted on a metal tube 19 constituting an extension of the anode supporting tube. A ring 20 is fastened by a vacuum-tight solder joint to the anode supporting tube. A gas-tight seal is provided by pressing a suitable washer 22 against the interstice between rings 20 and 18 by means of the ring 21 and the heavy threaded ring 23. The opposite end of the cathode chamber is rendered gas-tight by a solder joint between cathode stem 8 and plate 14. A guard ring 21 protects the cathode seal from damage by the discharge, the spacings between the adjacent parts being so close that a discharge does not occur between parts charged to unlike potentials.

The cathode housing 4 and the communicating small tube or anode housing 5 have spaced metal walls 29 and 30 which are arranged to be cooled by the circulation of a cooling fluid supplied by the inlet conduit 31 (Fig. 2), the fluid being discharged by the conduit 32. The course of the cooling fluid is confined by an appropriate longitudinal partition, as indicated at 34, which constrains the cooling fluid to flow the full length of the tubular extension 5 through the space between the walls 29, 30 on one side of the partition, the space between the anode and the end of the tube and returning through the space between the two walls on the opposite side of the partition.

The space within the hollow structure may be exhausted and charged with a suitable gas, as for example air, at an appropriate pressure by the conduit 33. The anode 6 may comprise a target 35 which is backed by a heat-absorbing plate 36. X-rays may leave the tubular chamber 5 by passing through a thin-walled window 37 which may consist of beryllium or other suitable material, or the electron beam may be utilized in other desired manner.

The interior of the device is kept at a low gas pressure by any suitable well known means, as for instance a pump and leak valve. Depending on the geometry of the tube, various pressures within a range of about 1 to 100 microns may be used. The interior geometry of the tube is such that the resultant electrostatic field constrains electrons leaving the tubular enclosure to travel at right angles to its surface under the influence of the impressed X-ray producing potential. When the electrode 7 functions as anode,

the electrons do not travel farther than about 5 millimeters before again impinging upon a conducting member; while electrons leaving the electrode 7 when functioning as cathode can travel several centimeters before reaching an opposing electrode. At a low gas pressure prevailing within the tube, for example 10 microns of mercury pressure, an electron has a mean free path of several centimeters so that electrons leaving the tubular electrode when it is negatively charged almost never collide with gas molecules. On the other hand, electrons leaving the electrode 7 when it is functioning as cathode will usually collide with and ionize gas molecules. Consequently, a self-perpetuating glow discharge can be set up in the region in front of the cathode 7 when it is negative with respect to the enclosing electrode. As no glow discharge can occur in the reverse direction, the device is rectifying, that is, transmits only half waves of an impressed alternating current.

During the glow discharge period positive ions bombard the cathode plate 11, thereby heating it and increasing its electron emission. These electrons travel perpendicularly outward from the cathode plate 11, ionizing the gas molecules with which they collide and forming a cloud of positive ions in the discharge space, the positive field of which constrains the discharge to pass down the center of the tubular housing 5. In other words, this cloud of ions focuses or constricts the electron stream into a fine beam which is coaxial with the anode housing, the discharge traversing the tubular extension 5 and impinging on the target 35. As a consequence the tubular extension 5 may be made of smaller diameter than in X-ray tubes heretofore provided for similar purposes.

Although one important field of usefulness of an X-ray device embodying my invention is the field of medicine and surgery, it is advantageous in other fields, for example in X-ray diffraction apparatus, as it permits bringing material to be examined close to the source of X-rays where the intensity of X-ray radiation is maximum.

What I claim as new and desire to secure by Letters Patent of the United States is:

1. An electron discharge device comprising an envelope adapted to function as an anode, a non-thermionic cathode enclosed thereby, means for insulating said electrodes from one another, a charge of gas at a pressure in the range of about 1 to 100 microns contained in said envelope and filling the space between said electrodes, the geometry and spacing of said electrodes being favorable to the operation of a self-perpetuating unidirectional gas ionization discharge therebetween which is constricted into a fine beam, and a tubular extension for said envelope so aligned that said beam discharge will traverse said extension.

2. An X-ray device comprising a metallic housing which functions also as an electrode, a second electrode enclosed by said housing, an outwardly projecting tubular extension for said housing having a diameter less than the diameter of said housing, an X-ray target located near the outer extremity of said extension, means for sealing and insulating said housing and a charge of gas at a pressure within the limits of 1 to 100 microns in said housing, the spacing and alignment of the electrodes being favorable to the conduction therebetween of a gas ionization discharge only when the enclosing electrode is positively

charged, the field of the positive ions resulting from said discharge through said gas causing constriction thereof, said tubular extension being aligned to cause said discharge to impinge upon the target therein.

3. An electronic device comprising a tubular anode including a target, a cooperating cathode enclosed within said tubular electrode remote from said target, sealing and insulating means between said electrodes, and a charge of gas at a pressure of between 1 and 100 microns in the discharge space between said electrodes, said tubular anode having a configuration and spacing which constrains an electronic discharge between said electrodes to pass in a direction substantially perpendicular to the face of said cathode through said gas and positive ions generated in said gas will cause such electronic discharge between said electrodes to assume the form of a constricted beam passing axially through said tubular electrode.

4. An X-ray device comprising a tubular electrode, a second electrode enclosed by said tubular electrode and located remote from one end thereof, means for hermetically sealing said tubular electrode, means for insulating said electrodes from one another, an attenuated gas in said tubular electrode at a pressure of about ten microns, the geometry of said electrodes and the pressure of said gas being so correlated that by ionization of said gas a self-sustaining discharge can occur therebetween which traverses longitudinally said tubular electrode, such discharge being constricted by the field of the positive ion column created in said gas by said discharge, the pressure of the gas contained in said tubular electrode being too low to permit of an ionization discharge in the space between juxtaposed parts of said electrodes and an X-ray target located at the extremity of said tubular electrode in position to have said constricted discharge impinge thereon.

5. An X-ray device comprising a tubular metal container which also functions as an electrode, a charge of gas therein at a pressure of about 10 microns, a non-thermionic cathode mounted therein, means for insulating and sealing said cathode from said container, the distance between said container and said cathode being shorter than the mean free path of an electron discharge therebetween a metal tube of lesser diameter extending longitudinally from said container, an X-ray target at the extremity of said container, and an X-ray transmitting window sealed into the wall of said tube adjacent said window.

6. An electron discharge device comprising a main tubular sealed metal envelope which functions as an electrode, a non-thermionic electrode within said tubular container, means for insulating said electrodes from one another, a gas at a pressure of about ten microns of mercury contained in said envelope, and a tubular extension of lesser diameter than said envelope aligned normal to said interior electrode and projecting outwardly from said envelope, said electrodes being constructed and spaced so closely as to permit passage of a gas ionization discharge through said gas only when said enclosed electrode is functioning as cathode, the field of the positive ions generated in said gas by such discharge focusing the discharge into a fine beam which traverses said tube.

DAVID HARKER.
